US00D547426S

(12) **United States Design Patent** (10) **Patent No.:** **US D547,426 S**
Pitchford et al. (45) **Date of Patent:** **** Jul. 24, 2007**

(54) **PORTABLE HEATER**

(75) Inventors: **Eric Pitchford**, Bowling Green, KY (US); **Henry Haley**, Bowling Green, KY (US); **Craig Higginbotham**, Bowling Green, KY (US); **Griffin Bland**, Bowling Green, KY (US)

(73) Assignee: **Desa IP, LLC**, Miami, FL (US)

(**) Term: **14 Years**

(21) Appl. No.: **29/250,115**

(22) Filed: **Nov. 2, 2006**

(51) **LOC (8) Cl.** **23-03**

(52) **U.S. Cl.** **D23/317; D23/342; D23/332; D23/336**

(58) **Field of Classification Search** **D23/314, D23/335, 332, 326, 336, 386, 339, 328, 317, D23/383, 327, 379, 324; 431/354, 173, 252; 432/222, 62; 126/110 C, 110 B; 392/488, 392/383, 374, 360, 364, 370, 366, 368, 369, 392/367; 165/122; 219/200-202, 520, 536, 219/532, 205; 237/28, 31, 35-37, 39, 12.3 B, 237/12.14; 415/95, 121.2, 247 R**
